UNITED STATES PATENT OFFICE

2,511,284

COUPLING

Fredric Meier, Chicago, Ill., assignor to Carnegie-Illinois Steel Corporation, a corporation of New Jersey

Application November 30, 1946, Serial No. 713,265

6 Claims. (Cl. 287—52.03)

1

This invention relates to couplings, and more particularly to couplings such as are used in imparting driving power to the pinion stands of rolling mills, although not limited thereto.

According to conventional rolling mill design, there is employed a pinion stand which connects through spindles with the necks of the rolls, the latter being journaled in the mill stand. In such an installation power is usually applied to the pinion stand from an adjacently disposed driving unit through a one-piece coupling box which receives very high stresses, and as a consequence frequently fails in service. Ordinarily the replacement of the conventional one-piece coupling box requires the shutting down of the mill for a substantial period of time. This is for the reason that the spindles between the mill stand and the pinion stand must be removed, and the pinion stand loosened and moved back on its supporting shoes in order that the coupling box may be lifted out between the end of the power shaft and the end of the pinion shaft, the new coupling box placed over the end of either of the two shafts and the pinion stand moved back to its original position on its supporting shoes, and a number of readjustments resorted to in order to properly position the pinion stand, after which the spindles must be replaced.

For the foregoing and other reasons the usual solid or one-piece coupling box of the type referred to is unsatisfactory. Not only is the replacement of the coupling box costly and troublesome due to the procedure described hereinbefore, but frequently an extended shut-down of the mill results in substantial loss in tonnage of the material to be rolled due to overheating in the heating furnace.

It is among the objects of the present invention to provide a coupling for rolling mills, heavy duty machinery, etc., which is very durable in service but may in case of breakage, or necessary repair, be replaced in but a very short interval of time.

Another object is the provision of a device of the type set forth immediately hereinbefore which is simple and inexpensive to manufacture, install and replace.

Still another object is the provision of a coupling of the class described which utilizes no exposed bolt heads and nuts which might endanger nearby workmen when the coupling box is rotating.

A further object is the attainment of the foregoing objectives without resort to the use of bolts for the transmission of power.

2

The invention, then, comprises the features hereinafter described and as particularly pointed out in the claims, the following description and the annexed drawings setting forth in detail certain illustrative embodiments of the invention, these being indicative of several of the number of ways in which the principles of the invention may be employed.

In said drawings:

- 10 Figure 1 is an end view of two cooperating coupling halves which when assembled form part of the device of the present invention;
- 15 Figure 2 is a sectional view on the line II—II of Figure 1;
- 20 Figure 3 is an end elevation of a yoke, two of which are employed to hold together the two split coupling halves shown in Figure 1;
- 25 Figure 4 is a side elevation of the yoke of Figure 3;
- 30 Figure 5 is a plan of the yoke of Figures 3 and 4;
- 35 Figure 6 is an end elevation of the split coupling halves of Figure 1 shown as maintained in assembled relationship by means of a pair of yokes of the type illustrated in Figures 3 through 5; and
- 40 Figure 7 is a side elevation of one of the split couplings illustrating at the top one of the yokes in attached position.
- 45 Referring more particularly to the drawings, the numerals 1 and 2 designate a pair of split coupling halves, both of which are provided along their adjoining edges with side flanges 3 which align with each other. Each of the side flanges 3 on the coupling half 1 is provided with an outwardly exposed shoulder 4, while on the adjoining surface of the side flange 3 of the oppositely disposed coupling half 2 there is formed a registering and cooperating recess 5. Through the media of the shoulders 4 and recesses 5, the side flanges 3, and accordingly the coupling halves 1 and 2, are properly centered with respect to each other.
- 50 In addition, the oppositely disposed side flanges 3 are bored as at 6 to permit the extension therethrough of bolts 7 which when provided with suitable nuts 8 (Figure 7) function to hold the two coupling halves 1 and 2 together.
- 55 The face of each of the side flanges 3 of the coupling half 2 is provided with a finished surface 10 tapered in a transverse plane inwardly from the body portion of the coupling half 2 (as shown most clearly in Figures 1 and 6), the purpose and function of which will appear more fully hereinafter.

3

Referring more particularly to Figures 3 through 5, the device of the invention comprises a yoke 12 which provides a pair of opposed finished surfaces 13 and 14 which are adapted to cooperate with the finished surfaces 15 and 16 on the side flanges 3 of the split coupling halves 1 and 2, respectively. As shown most clearly in Figure 6, the finished surface 13 of the yoke 12 and the cooperating finished surface 15 of the side flange 3 of the coupling half 1 are untapered, but the finished surface 14 of the yoke 12 and the cooperating finished surface 16 of the side flange 3 of the coupling half 2 are each provided with a definite taper. The degree of taper of the cooperating finished surfaces 14 and 16 is the same and of such angularity that a self-locking relationship is obtained when each of the yokes 12 is driven over an opposed pair of side flanges 3. I have found a taper of the order of one-quarter inch per foot to be satisfactory in the case of certain couplings of substantial size, but this of course is dependent upon a number of factors, and as such forms no part of the present invention.

After the two split coupling halves 1 and 2 are assembled, the bolts 7 are inserted in the bolt holes 6 and nuts 8 (Figure 7) employed in conjunction therewith to hold the two coupling halves together preparatory to receiving the yokes 12. The yokes 12 are then placed over their respective opposed pairs of lugs 3 and driven onto the said lugs to secure a solid fit.

Referring more particularly to Figures 4 and 5, each of the yokes has a pair of aligned and transversely extending slots 20 which provide clearance for the bolts 7. These slots 20 in the yokes 12 also enable the more ready loosening of the said yokes when it is desired to remove them as will appear immediately hereinafter. Each of the lugs 3 is provided with a transverse slot 21 which underlies the aligned transverse slots 20 in the cooperating yoke 12; and the bottoms of the said slots 20 are tapered. Such construction and arrangement permits the introduction of a drift pin (not shown) which may be driven in between the yoke 12 and the slots 21 in the next adjacent pair of lugs 3.

The outer ends of each cooperating pair of lugs 3 is conjointly recessed, as shown at 23, to permit of the retention of the heads of bolts 24, the shanks of which extend outwardly from between the said cooperating pair of lugs 3 and extend through and project from registering holes 26 in the adjacent yoke 12. The outer ends of the bolts 24 receive nuts 25. This construction and arrangement provides a safety measure for the prevention of the working loose of the yokes during operation.

In order that the coupling halves 1 and 2 may be easily handled they are provided on their exteriors with lifting lugs 28, and corresponding lifting lugs 29 may be provided on the exteriors of the yokes 12.

As to the interior contour of the coupling box, it is entirely dependent upon the shape of the shaft on which it is to be used, and as the device of the present invention is not concerned with flexibility, at least one end of the coupling should fit loosely on the said shaft.

While I have shown and described certain specific embodiments of the present invention, it will be readily understood by those skilled in the art that I do not wish to be limited exactly thereto, since various modifications may be made

4

without departing from the scope of the invention as defined in the appended claims.

I claim:

1. A coupling for driving connections comprising a body portion made up of a pair of split coupling halves, each of said coupling halves having a side flange projecting therefrom adjacent each adjoining edge in a direction normal to the longitudinal axis of said body portion, the flanges on one coupling half being adapted to align with the flanges on the other coupling half, connecting means passing through each pair of adjacent flanges to hold said coupling halves together, and a yoke member embracing each pair of adjacent flanges.
2. A coupling as defined in claim 1 which includes means for holding said yokes against sliding movement.
3. A coupling for driving connections comprising a body portion made up of a pair of split coupling halves, each of said coupling halves having a side flange projecting therefrom adjacent each adjoining edge in a direction normal to the longitudinal axis of said body portion, the flanges on one coupling half being adapted to align with the flanges on the other coupling half, a slidable yoke member embracing each pair of adjacent flanges, said yokes being slidable axially of said body portion, and means for holding said yokes against sliding movement.
4. A coupling as defined in claim 3 which includes connecting means passing through said aligned flanges to hold said coupling halves together.
5. A coupling for driving connections comprising a body portion made up of a pair of split coupling halves, each of said coupling halves having a side flange projecting therefrom adjacent each adjoining edge in a direction normal to the longitudinal axis of said body portion, the flanges on one coupling half being adapted to be aligned with the flanges on the other coupling half, the outer side of the flanges on at least one of said coupling halves being tapered in a plane normal to the longitudinal axis of said body portion inwardly from said body portion, a slidable yoke member embracing each pair of adjacent flanges, said yokes being slidable axially of said body portion, the adjacent surfaces of said flanges and said yokes being correspondingly shaped to contact each other to form a self-locking relationship, and means for holding said yokes against sliding movement.
6. A coupling as defined in claim 5 which includes bolt means passing through said aligned flanges to hold said coupling halves together.

FREDERIC MEIER.
